UNITED STATES PATENT OFFICE.

JOHN E. BUTCHER AND HOWARD B. HARRIS, OF GARBER, OKLAHOMA.

WIRE-CABLE CUTTER.

Application filed April 29, 1926. Serial No. 105,422.

This invention relates to improvements in wire cable cutters adapted for severing steel drilling cable or wire lines and is especially designed for use in connection with tools 5 now commonly used on the derrick floor of drilling wells.

An important object of the invention resides in the production of a device embodying engaging means for attachment to the 10 circular track of a well-known type of well jack and to provide cutter means slidably arranged within the body portion of said device and operable by certain parts of said jack.

Another object is to provide a device of 15 this character adaptable especially for use where well-drilling operations are carried out, and wherein the same may be efficiently operated without the exercise of special 20 knowledge or skill.

These and other objects of the invention will be more fully understood from the following detail description and accompanying drawings, in which—

Figure 1 is a side elevation of the device, the cutter member being advanced to approach the severing operation.

Figure 2 is a top plan view thereof.

Figure 3 is a vertical transverse sectional view taken substantially on the line 3—3 of Fig. 1; and

Figure 4 is another plan view of the device and illustrating diagrammatically the well jack and circular track used to facilitate 35 the operation of our device.

The construction and operation of well-drilling rigs being well understood by those skilled in this art it is not deemed necessary to describe same in detail. However, since

40 our device has been designed for use in connection with certain parts now commonly used on the derrick floor, attention is directed to Fig. 4 of the drawings wherein the numeral 5 denotes the well-known floor

45 circle having the usual track portion, T-shaped in cross-section, the top surface thereof bearing serrations 6 which engage the heel of the jack 7, the latter being adapted to break screw joints on drilling tools or

50 the like by clamping the same between the wrench posts 8. As stated hereinbefore, the above apparatus is already in use and obviously directly does not bear on our invention, but we have devised an arrangement

55 for use therewith, and which may be considered in the nature of an attachment.

Under these circumstances we naturally take advantage of the parts already in use and provide a simple structure operable by said parts and positioned at a point where the 60 cutting operation may be most expeditiously performed.

The device embodying our invention comprises a body portion 10, formed by the union of two substantially similar sections 65 11 and 12, each being extended laterally adjacent the base portion to lend rigidity to the general structure and at the same time provide sufficient material to support a longitudinal slot or groove which together 70 defines a T-shaped slot in cross-section, as shown at 13, Fig. 3. Each section is also longitudinally recessed to form the slot 14 for the reception of a cutter member 15, as will presently appear.

Said slot 14 may terminate within the body portion, or may be continued from end to end of the body portion, though our preferred structure will conform to the oblique termination of said cutter member 80 15 and have a slight extension at the top, as shown at 14^b to limit the sliding movement of said cutter member after its cutting operation.

After the sections 11 and 12 have been 85 formed to present their respective portions of the aforesaid slots, they may be securely bolted together, as indicated at 16, whereupon the recess 17 may be cut therein, said recess extending diagonally toward the base 90 of the body portion and there terminating into a transverse opening 18 which extends across said slot 14. Within this opening may be inserted a steel die 19 which is removable for renewing when worn.

The cutter member 15, hereinbefore referred to, is provided with a knife-edge 15^a, as clearly shown in Fig. 1, and is also provided with a slight forward extension 15^b for the obvious purpose of engaging or abutting the portion 14^b and limiting the forward travel of said member. The outer end of said member is provided with a head 20, and is arcuately disposed for engagement with the part 7 during the reciprocation of 105 said cutter member.

In operating our device, the body portion 10 is placed over the T-shaped rail 5 and if necessary the wrench post 8 may be advanced to abut the end of the body portion, the 110 cutter member is now withdrawn to clear the slot 17, whereupon the material to be

cut is slid into said slot and finally into the opening 18. The jack portion 7 is advanced to engage the head 20 of said cutter member and upon manipulation of said jack through 5 the medium of its socket 7^a and the cooperation of its ratchet movement, as is well understood, said cutter member is solidly and substantially brought against the wire cable with sufficient force to sever same.

10 While the present is a disclosure of the preferred embodiment of the invention, it is to be understood that the invention is not limited thereto, as various changes in the minor details of construction, proportion 15 and arrangement of parts may be resorted to without departing from the spirit of the invention as defined in the appended claims.

We claim:

1. In a cutting device, the combination 20 with an arcuate support having a rail portion and a jack adjustable longitudinally thereon, a cutter member engageable by said jack, and a two-part body portion removably mounted on the rail portion of 25 said support, having a longitudinally slot

to slidably receive said cutter member and a second slot extending from an edge of said body portion and terminating transversely through the first-mentioned slot to receive a length of cable therein.

2. In a cutting device, the combination 30 with an arcuate support having a rail portion and a jack adjustable longitudinally thereon, a cutter member engageable by said jack, and a body portion comprising two 35 similar sections and adapted to be removably mounted on said rail portion of said support, and having a longitudinal slot to slidably receive said cutter, said slot terminating in a reduced socket to limit the 40 forward travel of said cutter member, and a second slot extending from an edge of said body portion in a diagonal direction and terminating transversely through the first 45 mentioned slot in said body portion to receive a length of cable therein.

In testimony whereof we affixed our signatures.

JOHN E. BUTCHER.
HOWARD B. HARRIS.
